CLAIM

We claim the ornamental design for a vacuum-insulated glass plate, as shown and described.

DESCRIPTION

FIG. 1 is a front view of a vacuum-insulated glass plate according to the first embodiment of the present invention; FIG. 2 is a left side view thereof; FIG. 3 is a right side view thereof; FIG. 4 is a top view thereof; FIG. 5 is a bottom view thereof; FIG. 6 is an enlarged view of the section taken along line 6-6 in FIG. 1; FIG. 7 is a cross-sectional view taken long line 7-7 in FIG. 6; FIG. 8 is a cross-sectional view taken along line 8-8 in FIG. 6; FIG. 9 is a front view of a vacuum-insulated glass plate according to the second embodiment of the present invention; FIG. 10 is a left side view thereof; FIG. 11 is a right side view thereof; FIG. 12 is a top view thereof; FIG. 13 is a bottom view thereof; FIG. 14 is an enlarged view of the section taken along line 14-14 in FIG. 9; FIG. 15 is a cross-sectional view taken long line 15-15 in FIG. 14; FIG. 16 is a cross-sectional view taken along line 16-16 in FIG. 14; FIG. 17 is a front view of a vacuum-insulated glass plate according to the third embodiment of the present invention; FIG. 18 is a left side view thereof; FIG. 19 is a right side view thereof; FIG. 20 is a top view thereof; FIG. 21 is a bottom view thereof; FIG. 22 is an enlarged view of the section taken along line 22-22 in FIG. 17; FIG. 23 is a cross-sectional view taken long line 23-23 in FIG. 22; and,

(Continued)

FIG. 24 is a cross-sectional view taken along line 24-24 in FIG. 22.

The broken lines depict portions of the vacuum-insulated glass plate in which the design is embodied that form no part of the claimed design. Additionally, the dot-dash lines denote the boundary of the claim and form no part of the claimed design.
